UNITED STATES PATENT OFFICE.

WILLIAM W. HOFFMAN AND FRANCIS W. POWERS, OF WEST LAFAYETTE, INDIANA, ASSIGNORS TO ELECTRIC & STEAM RY. SUPPLY CO., OF LAFAYETTE, INDIANA.

TROLLEY-RETRIEVER.

SPECIFICATION forming part of Letters Patent No. 769,085, dated August 30, 1904.

Application filed October 19, 1903. Serial No. 177,694. (No model.)

To all whom it may concern:

Be it known that we, WILLIAM W. HOFFMAN and FRANCIS W. POWERS, citizens of the United States, both residing at West Lafayette, in the county of Tippecanoe and State of Indiana, have invented certain new and useful Improvements in Trolley-Retrievers; and we do hereby declare the following to be a full, clear, and exact description of the invention, such as will enable others skilled in the art to which it appertains to make and use the same.

Our invention relates to improvements in trolley-retrievers, and is especially designed to provide means to protect the overhead constructions of trolley-lines when the trolley-wheel jumps the trolley-wire.

The object of our present invention is to provide a purely mechanical means for accomplishing this end as distinguished from that class of devices wherein the upward movement of the trolley is arrested by means of mechanism controlled by an electromagnet excited by the current in the trolley-wire when the trolley-wheel leaves the wire.

Other advantages and features of novelty will hereinafter more fully appear, and to more clearly understand our invention reference is had to the accompanying drawings, illustrating the same, wherein like characters designate like parts in the several views, and in which—

Figure 1 represents a front elevation of the assembled device, the front plate for the casing and the upright support for the central spindle being omitted and a portion of the winding-reel cut away to show the interior mechanism more clearly. Fig. 2 is a vertical transverse section on the lines 22 of Fig. 1. Fig. 3 is a detail view of the rotary clutch-plate mounted adjacent the winding-drum, showing the location of the pivoted dogs carried by the winding-drum with respect to the clutch-plate and a part of the clutch-plate being broken away. Fig. 4 is a substantially similar view to Fig. 1, showing an auxiliary automatic locking device between the clutch-disk and winding-drum, a section being taken through the winding-drum adjacent the in-

ner disk K'; and Fig. 5 is a fragmentary detail sectional view of the top portion of the 50 mechanism on the line 44 of Fig. 4.

A represents a box or casing, preferably constructed of metal and of such dimensions as to be readily removable to either end of the car.

B is a central spindle supported at one end in the rear of the casing and at its other end by an upright support or bracket B' in any suitable manner, such as by means of the screw b. C is a hub or sleeve rotatably supported on said spindle B and provided with the annular disk D, preferably formed integral therewith. This disk D, as illustrated in Fig. 2, is provided at its outer end with an inwardly-extending enlarged portion D' 60 therearound, forming an annular recess D^o, and extending upwardly at right angles from this enlarged portion is an annular flange D².

On the inner face of the enlarged annular portion D' and extending inwardly into the 70 recess D^o are a plurality of circumferentially-disposed ratchet-teeth d. On the inner face of the annular flange D² is located a lug E, and adjacent said lug forming a continuation of the circumferential face of the flange 75 D² is a projecting tooth or lug E.

F designates a catch or dog located at the upper end of the clutch-disk D in the space formed by the annular flange D² and the enlarged portion D'. This catch or dog F is 80 pivotally supported by means of the shaft f passing through an aperture in the annular flange D², the other end of the shaft f, carrying an arm f', provided with the transversely-disposed arm or lever F', adapted to project 85 above the winding-drum in the path of the trolley-rope. It is obvious that the arms F and f' may be secured to the shaft f in any suitable way; but we prefer that the shaft and arms be made integral and bent to the 90 desired shape, as shown in the drawings. This crank-like arm f' is normally held in engagement with the underneath face of the lug E by any suitable means. In the drawings we have illustrated this by a flat metallic spring 95 f², fastened at one end, as by a screw, to the

outer surface of the enlarged portion D' and extending at its other end beneath the catch or dog F.

Located between the clutch-disk D and the rear face of the casing is a motor-spring G of a strength sufficient to overcome the tension of the springs controlling the trolley-pole. This spring G surrounds the inner end of the hub or sleeve C, being secured thereto at one end in any suitable manner—as at G', for instance—by being hooked into a groove formed in the sleeve, and the other end of the spring is suitably secured to a stationary support—as, for instance, to the abutment H, formed integral with the casing A. The outward play of the spring is limited by the abutments H, H', H'', and H'', all of which are suitably secured to and project inwardly from the sides of the casing.

I designates the winding - drum for the trolley-rope, and comprises the annular side plates K K' and the transverse portion K''. This drum is rotatably supported on and movable independently of the hub or sleeve C, the side wall K' being disposed immediately adjacent to the annular recess D'', and forming therewith a closed chamber for the reception of operating-dogs carried by the drum, adapted to become engaged at the proper moment with the internal ratchet-teeth d. These dogs J are pivotally supported on the plate K' of the drum by means of the pivot-screws j therethrough and are provided on their outer surface with the projecting teeth J' in proximity to the internal ratchet-teeth d of the ratchet-disk.

The teeth J' are normally held out of engagement with the ratchet-teeth d by means of a suitable spring engaging the pivoted dogs J. These springs are preferably adjustable to increase or decrease their tension for regulating the movement of the pivoted dogs. In the drawings I have illustrated these adjustable springs as comprising a curved flat piece of resilient metal j'', engaging at one end the upper face of the pivoted dogs and at its other end adjustably secured, by means of the screws j'', to the supporting blocks or projections J'', suitably secured to the outer face of the annular disk K' of the drum. These blocks or projections may preferably be formed integral with the drum and are preferably so disposed, as shown in Fig. 3, to serve as stops, engaging the free ends of the pivoted dogs and limiting the inward play of the same.

Within the drum I is located a light disk L, resting against the ribs l, which forms a chamber or casing with the side plate K of the drum, within which is located a suitable flat coil-spring M, connected at one end in any suitable manner to the hub or sleeve C, as at m, and at its other end to the inner face of the drum. This spring is sufficiently strong to actuate the drum and wind thereon

the trolley-rope N, which is suitably secured thereto for retaining the trolley-rope taut, but not strong enough to overcome the tension of the springs operating the trolley-pole, so that the action of the drum will at all times take up the slack of the trolley-rope, but will allow the rope to pay out to suit the variations in the height of the trolley-wire.

O is a detent-bar provided at its forward end with the downwardly-projecting tooth or detent O' and at its rear end with the projection or tooth O'', so formed thereon as to be located out of the path of the projecting tooth E, but in the path of the pivoted dog or catch F. On the forward end of the detent-bar is formed an offset O''', provided with a transverse pin or lug o'', and this offset is located adjacent the projecting shoulder H' on the abutment H'', the downward movement of the offset being limited by the transversely-disposed pin o', projecting from the shoulder H'' beneath the offset O'''.

P is a transversely - disposed abutment, preferably formed integral with the upper inside face of the casing and adapted to be engaged by the offset O''' of the detent-arm at the proper time. The rear enlarged portion of the detent-bar O is slotted, as at O', and, pivotally supported by means of the pivot-screw r'', passes through a bracket R' on one side of the detent-bar, through the slot O', and screwing at its inner end into a post R, projecting from the rear side of the casing, the post R being reinforced by the depending web r, which joins it to the top of the casing.

Between the detent-bar and the inner faces of the post R and the bracket R' are interposed the friction-washers r', of any suitable material, such as rubber, or the like. (Shown in Figs. 1 and 4.) These friction-washers allow the longitudinal movement of the detent-bar O, but retard its movement to a certain extent, and this may be further regulated by tightening or loosening the screw r''.

We provide means at the forward end of the detent-bar normally tending to press the same upwardly, and in the drawings we have illustrated this means as comprising a resilient metallic strip Q, adjustably secured at one end to the casing by the screw q and at its other end adapted to project beneath the transverse pin o'' on the offset O'''.

a designates a handle on the top of the casing, and a' a hook under which the trolley-rope may be passed to hold it firmly when the casing is being shifted from one end of the car to the other.

It will be obvious that duplicate mechanism might be arranged on the forward and rear ends of the car and secured firmly thereto; but in practical operation for the sake of cheapness it is preferable that the casing and mechanism be made portable, as described, and provided with suitable locking means whereby it may be easily and quickly attached to

or detached from the car proper. To accomplish this end, we have shown a metal frame, preferably triangular in shape, as indicated at 1, adapted to be secured to the dashboard of a car by the bolts 2, and at the bottom of this triangular frame are located the upwardly-extending hooks 3, which are adapted to project into holes provided in the bottom of the portable casing.

At the top of the frame 1 is provided an inwardly-projecting shoulder 4, to the inner face of which is pivotally secured the button 5, adapted to engage the inner face of a projection 6 on the casing, so located as to extend upwardly beneath the inwardly-extending shoulder 4, as clearly indicated in Fig. 2.

In Figs. 4 and 5 we have illustrated a modified arrangement whereby an auxiliary locking means is provided on the clutch-disk D, adapted to be automatically brought into locking engagement with the side face K' of the drum I for locking said disk and drum together should the pivoted dogs J by any means become disengaged from the ratchet-teeth d, while the winding mechanism is released with respect to the detent on the detent-bar, before described. For this purpose we provide a pawl N', having a suitably-shaped upwardly-projecting lug N² and a tail member N³, which pawl is pivotally supported on a stud N⁴, projecting outwardly from the flanged portion D².

The upwardly-projecting lug N² is disposed alongside of the projecting tooth E on the flange D², and for this purpose in this construction the projecting tooth E might simply be an angularly-raised portion on the circumferential surface of the flange. It will be observed that the inner face of the lug N² is normally held in engagement with the detent O' by means of a suitable spring n³, secured to the flange D² and projecting beneath the tailpiece N³, and while in this position the pawl member N' is held out of engagement with, but disposed immediately above, the inner disk K' of the winding-drum I, the periphery of this disk being provided with a plurality of notches N⁵, disposed therearound.

The operation of the mechanism is as follows: The drum I, being loosely mounted on the sleeve or hub C and being actuated by the coil-spring M, revolves to take up the slack of the trolley-rope, the strength of the spring M being sufficient for this purpose, but insufficient for holding the drum I against rotation in the opposite direction when the trolley-pole rises to conform with the variations in height of the trolley-wire, so that the trolley-rope by this construction is normally held taut. When, however, the trolley leaves the wire it springs forward with great force and starting to unwind the drum I rapidly with a jerk throws the dogs J downwardly against the tension of the springs j', and the teeth J' thereon being thrown outwardly into the path

of the ratchet-teeth d of the clutch-disk D will jar the disk D backwardly sufficiently to allow the action of the spring Q to move the forward end of the detent-bar O upwardly, thereby withdrawing the detent or tooth O' out of engagement with the tooth E on the clutch-disk, whereupon the action of the strong coil-spring G will immediately rotate the clutch-disk D forwardly, and the clutch-disk being now locked to the winding-drum I by the interposed pivoted dogs J the trolley-rope will be wound thereon, bringing the trolley-pole downwardly and out of reach of the overhead cross-wires. During the initial rotation of the clutch-disk D the lever-arm F', being disposed transversely of the winding-drum, is engaged by the trolley-rope and swung downwardly to a position relatively to the drum corresponding to the position indicated by the dotted lines in Fig. 1, so that the arm F' will rest on the periphery K² of the drum and the continued rotation of the drum will wind the rope on the drum over the arm F', lying transversely thereon. The dog F is also moved downwardly and out of the path of the tooth O² on the detent-bar. To set the mechanism again, the trolley-rope is pulled upwardly, the springs controlling the trolley-pole assisting the operation, and the rope being unwound from the drum will release the lever-arm F', which will then spring upwardly by the action of the spring j', its upward movement being limited by the lock or stop E'. The dog F having thus assumed its normal position will upon a further rearward rotation of the clutch-disk engage the inner face of the tooth O², thus inwardly moving the forward end of the detent-bar downwardly, thence sliding the detent-bar rearwardly as far as permitted by the slot O⁴, in which position the offset O³ is moved beneath the abutment P, holding the forward end of the detent-bar down. The manual pull on the rope being then released, the strong spring G will overcome the tension of the springs on the trolley-pole and again rotate the winding mechanism forwardly until the tooth E engages the detent O', which is now held in the path of the tooth E, and the continued forward rotation of the clutch-disk D forces the detent-bar O forwardly as far as the slot O⁴ will permit, which is its normal position, as shown in the drawings. A slight pull down on the trolley-rope when the mechanism is in this position will allow the winding-drum to rotate forwardly a sufficient distance to bring the teeth J' beyond the point of the ratchet-teeth d, when the action of the springs j' will again move the pivoted dogs J into their normal position. The friction-washers r' will hold the detent O' in engagement with the lug E against the action of the spring Q, the angularly-disposed surfaces of the detent O' and tooth E furthering this end. When the mechanism is shifted from one end of the car to the other, the trolley-rope is first placed

under the hook a' on the top of the casing, thus locking the winding-drum against movement, and the tension of the trolley-spring on the trolley-pole will help to support the 5 weight of the mechanism while being moved.

The operation of the modified mechanism shown in Figs. 4 and 5 is substantially similar, as heretofore described, except that at the same time the tooth E is disengaged from 10 the detent O' the lug N^2 is also released and the pawl member N' is pressed down and rests on the cut-away face n^5 of the drum-disk K' by the action of the spring n^3 thereon. When the pawl is in this position, it is obvious that 15 if the pivoted dogs J should become disengaged from the ratchet-teeth d the pawl member N' would immediately lock the clutch-disk and winding-drum by being brought into engagement with the nearest notch N^5 of the 20 drum-disk K'. Also when the mechanism is being reset and the detent-bar O has been moved downwardly and backwardly by the lug F engaging the tooth O², the forward end being now held beneath the projecting bar P, 25 as before described, when the clutch-disk is rotated forwardly, the parts being in this position, the forward end of the lug N^2 is engaged by the detent O' and the auxiliary pawl is raised upwardly toward its normal position 30 until the tooth E also engages the detent O' and the mechanism is thus reset.

It will be understood that we do not wish to limit ourselves to the exact details as illustrated and described, as it is obvious that many 35 modifications might be made in actual construction without departing from the spirit of our invention; but

What we claim is—

1. In trolley-retrieving mechanism, the combination with operative means connected to 40 the trolley-rope, supplemental movable means normally held against movement, and driving mechanism for said first-mentioned operative and supplemental means, of a locking device 45 for said supplemental means, means for automatically locking said first-mentioned operative means and supplemental means and releasing said locking device upon the sudden upward movement of the trolley-pole, and 50 auxiliary locking means automatically set upon the release of said supplemental means and adapted to lock together said first-mentioned operative and supplemental means upon the accidental displacement of said main locking 55 means.

2. In trolley-retrieving mechanism, the combination with operative means connected to the trolley-rope, supplemental movable means normally held against movement and driving 60 mechanism for said first-mentioned operative and supplemental means, of a locking device for said supplemental means, mechanically-operated means for automatically locking said first-mentioned operative means and supplemental 65 means and releasing said locking device with said first-mentioned operative and supplemental means upon the accidental displacement of said main locking means.

vice upon the sudden upward movement of the trolley-pole, and auxiliary locking means automatically set upon the release of said supplemental means and adapted to lock together said first-mentioned operative and supplemental means upon the accidental displacement of 70 said main locking means.

3. In trolley-retrieving mechanism, the combination with a winding-drum connected to the trolley-rope, rotary means normally locked 75 against movement and driving mechanism for said winding-drum and rotary means, of a locking device for said rotary means, means for automatically locking said drum and rotary means and releasing said locking device 80 upon the sudden upward movement of the trolley-pole, and auxiliary locking means automatically set upon the release of said rotary means and adapted to lock together said drum and rotary means upon the accidental displacement 85 of said main automatic locking means.

4. In trolley-retrieving mechanism, the combination with operative means connected to the trolley-rope, supplemental movable means normally held against movement, and driving 90 mechanism for said first-mentioned operative and supplemental means, of a locking device for said supplemental means, means for automatically locking said first-mentioned operative means and supplemental means and releasing said locking device upon the sudden 95 upward movement of the trolley-pole, and auxiliary locking means automatically set upon the release of said supplemental means and adapted to lock together said first-mentioned operative and supplemental means upon the accidental displacement of 100 said main locking means, comprising a pawl pivotally mounted on said supplemental means and adapted to be brought into locking engagement with 105 said first-mentioned operative means.

5. In trolley-retrieving mechanism, the combination with operative means connected to the trolley-rope, supplemental means normally held against movement and driving mechanism for said first-mentioned operative and supplemental means, of a locking device for said supplemental means, mechanically-operated means for automatically locking said first-mentioned operative means and supplemental 110 means and releasing said locking device upon the sudden upward movement of the trolley-pole, and auxiliary locking means automatically set upon the release of said supplemental means and adapted to lock together said 115 first-mentioned operative and supplemental means and releasing said locking device upon the sudden upward movement of the trolley-pole, and auxiliary locking means automatically set upon the release of said supplemental means and adapted to lock together said 120 first-mentioned operative and supplemental means upon the accidental displacement of said main locking means, comprising a pawl pivotally mounted on said supplemental means and adapted to be brought into locking engagement with said first-mentioned operative means.

6. In trolley-retrieving mechanism, the combination with a winding-drum connected to the trolley-rope, rotary means normally locked 125

against movement and driving mechanism for said winding-drum and rotary means, of a locking device for said rotary means, means for automatically locking said drum and rotary means and releasing said locking device upon the sudden upward movement of the trolley-pole, and auxiliary locking means automatically set upon the release of said rotary means and adapted to lock together said drum and rotary means upon the accidental displacement of said main automatic locking means, comprising a pawl pivotally mounted on said rotary means and adapted to be brought into locking engagement with said winding-drum.

7. In trolley-retrieving mechanism, the combination with means connected to and coöperating with the trolley-rope for normally holding said rope taut, of movable means, provided with ratchet-teeth, normally locked against movement, driving mechanism therefor of sufficient power to overcome, when released, the upward tension on the trolley-pole, a locking device for said movable means, means for automatically locking said first-mentioned and movable means and releasing said locking device, comprising interposed pivoted dogs carried by said first-mentioned means and adapted to be thrown into engagement with said ratchet-teeth upon the sudden upward movement of the trolley-pole, and means automatically set upon the release of said movable means and adapted to lock said first-mentioned means and movable means together upon the accidental displacement of said pivoted dogs when in their locked position.

8. In trolley-retrieving mechanism, the combination with a winding-drum connected to the trolley-rope and means coöperating therewith for normally holding said trolley-rope taut, of rotary means, provided with ratchet-teeth, normally locked against movement, driving mechanism therefor of sufficient power to overcome, when released, the upward tension on the trolley-pole, a locking device for said rotary means, means for automatically locking said drum and rotary means and releasing said locking device, comprising interposed pivoted dogs carried by said drum and adapted to be thrown into engagement with said ratchet-teeth upon the sudden upward movement of the trolley-pole, and auxiliary means automatically set upon the release of said rotary means and adapted to lock said winding-drum and rotary means together upon the accidental displacement of said pivoted dogs when in their locked position.

9. In trolley-retrieving mechanism, the combination with means connected to and coöperating with the trolley-rope for normally holding said trolley-rope taut, of a rotatably-supported disk, provided with a plurality of circumferentially-disposed ratchet-teeth, normally locked against rotation, driv-

ing mechanism therefor of sufficient power to overcome, when released, the upward tension on the trolley-pole, a locking device for said rotary disk, means for automatically locking said first-mentioned means and rotary disk and releasing said locking device, comprising interposed pivoted dogs carried by said first-mentioned means adapted to be thrown into engagement with said ratchet-teeth upon the sudden upward movement of the trolley-pole, and auxiliary means automatically set upon the release of said rotary disk and adapted to lock said first-mentioned means and rotary disk together upon the accidental displacement of said pivoted dogs when in their locked position.

10. In trolley-retrieving mechanism, the combination with means connected to and coöperating with the trolley-rope for normally holding said trolley-rope taut, of a rotary support provided with a plurality of circumferentially-disposed inwardly-extending ratchet-teeth, normally locked against rotation, driving mechanism therefor of sufficient power to overcome, when released, the upward tension on the trolley-pole, a locking device for said rotary support, means for automatically locking said first-mentioned means and rotary support and releasing said locking device, comprising interposed pivoted dogs carried by said first-mentioned means and adapted to be thrown into engagement with said ratchet-teeth upon the sudden upward movement of the trolley-pole, and auxiliary means automatically set upon the release of said rotary support and adapted to lock said first-mentioned means and rotary support together upon the accidental displacement of said pivoted dogs when in their locked position.

11. In trolley-retrieving mechanism, the combination with a winding-drum connected to the trolley-rope and means coöperating with said drum for normally holding said trolley-rope taut, of a rotatably-supported disk, provided with a plurality of circumferentially-disposed ratchet-teeth normally locked against rotation, driving mechanism therefor of sufficient power to overcome, when released, the upward tension on the trolley-pole, a locking device for said rotary disk, means for automatically locking said drum and rotary disk and releasing said locking device, comprising interposed pivoted dogs carried by said drum adapted to be thrown into engagement with said ratchet-teeth upon the sudden upward movement of the trolley-pole, and auxiliary means automatically set upon the release of said rotary disk and adapted to lock said winding-drum and rotary disk together upon the accidental displacement of said pivoted dogs when in their locked position.

12. In trolley-retrieving mechanism, the combination with a winding-drum connected to the trolley-rope and means coöperating with said drum for normally holding said rope taut,

- of a rotatably-supported disk normally locked against rotation, provided with an inwardly-extending annular enlarged portion, a plurality of internal ratchet-teeth formed on said 5 enlarged portion, driving mechanism for said rotary disk of sufficient power to overcome, when released, the upward tension on the trolley-pole, a locking device for said rotary disk, means for automatically locking said 10 drum and rotary disk and releasing said locking device, comprising interposed pivoted dogs carried by said drum and adapted to be thrown outwardly into engagement with said internal ratchet-teeth upon the sudden upward 15 movement of the trolley-pole, and auxiliary means automatically set upon the release of said rotary disk and adapted to lock said winding-drum and rotary disk together upon the accidental displacement of said pivoted dogs 20 when in their locked position.

13. In trolley-retrieving mechanism, the combination with means connected to and co-operating with the trolley-rope for normally holding said rope taut, of movable means, 25 provided with ratchet-teeth, normally locked against movement, driving mechanism therefore of sufficient power to overcome, when released, the upward tension on the trolley-pole, a locking device for said movable means, 30 means for automatically locking said first-mentioned and movable means and releasing said locking device, comprising interposed pivoted dogs carried by said first-mentioned means and adapted to be thrown into engagement with said ratchet-teeth upon the sudden 35 upward movement of the trolley-pole, and means automatically set upon the release of said movable means and adapted to lock said first-mentioned means and movable means 40 together upon the accidental displacement of said pivoted dogs when in their locked position, comprising a spring-operated dog pivotally supported on said movable means adjacent said first-mentioned means.

14. In trolley-retrieving mechanism, the combination with the winding-drum, of rotary means, provided with ratchet-teeth, normally locked against movement, means normally tending to rotate said drum and rotary means, 50 a locking device for said rotary means, means for automatically locking said drum and rotary means and releasing said locking device, comprising interposed pivoted dogs carried by said drum and adapted to be thrown into engagement with said ratchet-teeth upon the sudden upward movement of the trolley-pole, and auxiliary means automatically set upon the release of said rotary means and adapted to lock said winding-drum and rotary means 55 together upon the accidental displacement of said pivoted dogs when in their locked position, comprising a spring-operated dog pivotally supported on said rotary means adjacent said winding-drum.

15. In trolley-retrieving mechanism, the

combination with means connected to and co-operating with the trolley-rope for normally holding said trolley-rope taut, of a rotatably-supported disk, provided with a plurality of circumferentially-disposed ratchet-teeth, normally locked against rotation, driving mechanism for said disk, a locking device for said rotary disk, interposed pivoted dogs carried by said first-mentioned means adapted to be thrown into engagement with said ratchet-teeth upon the sudden upward movement of the trolley-pole, and auxiliary means automatically set upon the release of said rotary disk and adapted to lock said first-mentioned means and rotary disk together upon the accidental displacement of said pivoted dogs when in their locked position, comprising a spring-operated dog pivotally supported on said rotary disk adjacent said first-mentioned means. 70 75 80

16. In trolley-retrieving mechanism, the combination with means connected to and co-operating with the trolley-rope for normally holding said trolley-rope taut, of a rotary support provided with a plurality of circumferentially-disposed inwardly-extending ratchet-teeth, normally locked against rotation, driving mechanism for said rotary support, a locking device for said rotary support, interposed pivoted dogs carried by said first-mentioned means and adapted to be thrown into engagement with said ratchet-teeth upon the sudden upward movement of the trolley-pole, and auxiliary means automatically set upon the release of said rotary support and adapted to lock said first-mentioned means and rotary support together upon the accidental displacement of said pivoted dogs when in their locked position, comprising a spring-operated dog pivotally supported on said rotary support adjacent said first-mentioned means. 90 95 100 105

17. In trolley-retrieving mechanism, the combination with the winding-drum, of a rotatably-supported disk, provided with a plurality of circumferentially-disposed ratchet-teeth normally locked against rotation, driving mechanism for said drum and rotary disk, a locking device for said rotary disk, interposed pivoted dogs carried by said drum adapted to be thrown into engagement with said ratchet-teeth upon the sudden upward movement of the trolley-pole, and auxiliary means automatically set upon the release of said rotary disk and adapted to lock said winding-drum and rotary disk together upon the accidental displacement of said pivoted dogs when in their locked position, comprising a spring-operated dog pivotally supported on said rotary disk adjacent said winding-drum. 110 115 120 125

18. In trolley-retrieving mechanism, the combination with the winding-drum, of a rotatably-supported disk normally locked against rotation, provided with an inwardly-extending annular enlarged portion, a plurality of internal ratchet-teeth formed on said enlarged portion, driving mechanism for said drum and 130

rotary disk, a locking device for said rotary disk, interposed pivoted dogs carried by said drum and adapted to be thrown outwardly into engagement with said internal ratchet-teeth 5 upon the sudden upward movement of the trolley-pole, and auxiliary means automatically set upon the release of said rotary disk and adapted to lock said winding-drum and rotary disk together upon the accidental dis- 10 placement of said pivoted dogs when in their locked position, comprising a spring-operated dog pivotally supported on said rotary disk adjacent said winding-drum.

19. In trolley - retrieving mechanism, the combination with the winding-drum, a normally locked rotary support and means tending to rotate said drum and rotary support, of a longitudinally-movable detent normally engaging said rotary support, and mechanically- 20 operated means for automatically locking said drum and rotary support and releasing said detent upon the sudden upward movement of the trolley-pole.

20. In trolley - retrieving mechanism, the combination with the winding-drum, a normally-locked rotary support and means tending to rotate said drum and rotary support, of a longitudinally-movable pivoted detent normally engaging said rotary support, means 30 for exerting upward pressure on said detent, and mechanically-operated means for simultaneously locking said drum and rotary support and releasing said detent upon the sudden upward movement of the trolley-pole.

21. In trolley - retrieving mechanism, the combination with the winding-drum, a normally locked rotary support, and means tending to rotate said drum and rotary support, of a tooth on said rotary support, a longitudinally-movable pivoted detent normally engaging said tooth, means exerting upward pressure on said detent, and mechanically-operated means for simultaneously locking said drum and rotary support and releasing said detent. 40

22. In trolley - retrieving mechanism, the combination with the winding-drum, a normally locked rotary support, and means tending to rotate said drum and rotary support, of a longitudinally-movable detent normally engaging said rotary support, friction members 50 engaging said detent for controlling its longitudinal movement, and means for automatically locking said drum and rotary support and releasing said detent upon the sudden upward movement of the trolley-pole.

23. In trolley - retrieving mechanism, the combination with the winding - drum, normally locked rotary support, and means tending to rotate said drum and rotary support, of 60 a longitudinally-movable pivoted detent normally engaging said rotary support, friction washers engaging said detent for controlling its longitudinal movement, means for exerting upward pressure on said detent, and means 70 for simultaneously locking said drum and ro-

tary support and releasing said detent upon the sudden upward movement of the trolley-pole.

24. In trolley - retrieving mechanism, the combination with the drum, a normally locked rotatably-mounted support, and means tending to rotate said drum and rotary support, of a detent-bar capable of longitudinal and vertical movement, provided with a tooth at its rear end and a detent at its forward end normally engaging said rotary support, means normally tending to unlock said detent from said drum, means for simultaneously locking said drum and rotary support and releasing said detent upon the sudden upward movement of the trolley-pole, and means carried by said rotary support for engaging said rear tooth at a predetermined point of said rotary support's rearward rotation for resetting said detent. 75

25. In trolley - retrieving mechanism, the combination with the drum, rotary support, and means for rotating and interlocking same, of a detent capable of longitudinal and vertical movement, normally engaging said rotary support, and means adapted to engage said detent at a predetermined point of the rearward rotation of said rotary support, when resetting, comprising a dog pivotally mounted on said rotary support, and provided with an arm 80 extending transversely of said drum. 90

26. In trolley - retrieving mechanism, the combination with the drum, a normally locked rotatably-mounted support and means tending to rotate said drum and rotary support, of a detent-bar capable of longitudinal and vertical movement provided with a tooth at its rear end and a detent at its forward end normally engaging said rotary support, means exerting upward pressure on the forward end of said 100 detent-bar, mechanically-operated means for simultaneously locking said drum and rotary support and releasing said detent upon the sudden upward movement of the trolley-pole, and a pivoted dog carried by said rotary support, 105 held out of engagement with said rear tooth of said detent-bar during the forward rotation of said rotary support, but adapted to project upwardly and engage said rear tooth at a predetermined point of said rotary support's rearward rotation. 110

27. In trolley - retrieving mechanism, the combination with the drum, a normally locked rotatably-mounted support and means tending to rotate said drum and rotary support, of a detent-bar capable of longitudinal and vertical movement provided with a tooth at its rear end and a detent at its forward end normally engaging said rotary support, means exerting upward pressure on the forward end of said 120 detent-bar, mechanically-operated means for simultaneously locking said drum and rotary support and releasing said detent upon the sudden upward movement of the trolley-pole, and means adapted to engage the rear tooth 125 130

of said detent-bar at a predetermined point of the rearward rotation of said rotary support, comprising a dog pivotally mounted on said rotary support and provided with an arm extending transversely across said winding-drum.

28. In trolley-retrieving mechanism, the combination with the winding-drum, a normally locked rotatably-mounted support and means tending to rotate said drum and rotary support, of a tooth on said rotary support, a pivoted detent-bar provided with a detent normally engaging said tooth, means exerting upward pressure on the free end of said detent-bar, mechanically-operated means for locking said drum and rotary support and releasing said detent upon the sudden upward movement of the trolley-pole, and an auxiliary locking means for said drum and rotary support, comprising a spring-operated pivoted pawl, carried by said support adjacent said winding-drum, and provided with an upwardly-extending lug adapted to normally engage said detent.

29. In trolley-retrieving mechanism, the combination with a rotatably-supported drum connected to the trolley-rope, and means for actuating said drum, of a rotatably-supported disk adjacent said drum, driving mechanism connected to said disk of sufficient power to overcome, when released, the upward tension on the trolley-pole, a plurality of ratchet-teeth formed on said disk, a locking-tooth formed on said disk, a detent-bar pivotally supported at its rear end and capable of longitudinal movement, a detent carried by the forward end of said detent-bar normally engaging said locking-tooth for locking said rotary disk, a tooth formed on the rear end of said detent-bar, means exerting upward pressure on the forward end of said detent-bar, a spring-operated pivoted dog carried by said rotary disk, an arm fast to said pivoted dog and projecting transversely above said winding-drum, means for limiting the upward movement of said projecting arm, and means for automatically locking said drum and rotary disk and releasing said detent.

30. In trolley-retrieving mechanism, the combination with the winding-drum, a rotatably-mounted support, and means for actuating said drum and support, of a detent-bar provided with a detent normally engaging and locking said rotary support and provided at its rear end with a longitudinal slot, a suitable support extending adjacent said slotted portion of said detent-bar, a pivot-pin carried by said detent-bar support and passing through said slot, friction-washers interposed between said detent-bar and said support, adjacent said slot, for controlling the longitudinal movement of said detent-bar, and mechani-

ically-operated means for simultaneously locking said drum and rotary support and releasing said detent upon the sudden upward movement of the trolley-pole.

31. In trolley-retrieving mechanism, the combination with a suitable casing, of a winding-drum rotatably mounted therein and means for actuating said winding-drum, a rotatably-mounted support adjacent said winding-drum, a coil motor-spring connected to said rotary support, abutment-posts carried by said casing and extending transversely of said motor-spring for limiting its outward play, a pivoted detent normally engaging said rotary support for locking the same against movement, means exerting upward pressure on said detent at its forward end, and mechanically-operated means for simultaneously locking said drum and releasing said detent upon the sudden upward movement of the trolley-pole.

32. In trolley-retrieving mechanism, the combination with a suitable casing, formed with a central hollow shoulder extending therein from its rear face, a fixed spindle mounted at one end within said hollow shoulder, an upright support disposed adjacent the front face of the casing, supporting the other end of said spindle, a hub rotatably supported on said spindle, a disk carried by said hub near one end thereof, a winding-drum loosely mounted on the other end of said hub, means so interposed between said drum and disk as to allow of their independent rotation relatively to each other, and means for locking said drum and disk for conjointly rotating them upon the sudden upward movement of the trolley-pole.

33. In portable trolley-retrieving mechanism, the combination with a triangular frame, adapted to be carried on the front and rear of the car, said frame provided at its base with upwardly-extending lugs and at its apex with a pivoted locking-button, of a portable casing provided on its underneath surface with apertures adapted to register with said lugs, a projection on the upper rear face of said casing adapted to be engaged by said locking-button, mechanism within said casing connected to and normally holding the trolley-rope taut, and mechanism co-operating with said trolley-rope-controlling mechanism, mechanically operated by the sudden upward movement of said trolley-pole for retrieving said trolley-pole.

In testimony whereof we affix our signatures in presence of two witnesses.

WILLIAM W. HOFFMAN.
FRANCIS W. POWERS.
